[57] CLAIM

The ornamental design for bezel ring for analog wristwatch,
as shown and described.

DESCRIPTION

FIG. 1 is a top plan view of my improved bezel ring for an
analog wristwatch;

FIG. 2 is a right side elevational view thereof;

FIG. 3 is a left side elevational view thereof;

FIG. 4 is a front end elevational view thereof;

FIG. 5 is a rear end elevational view thereof; and,

FIG. 6 is a plan view thereof.

The watchcase and strap, portions of which are shown in
dashed and phantom lines in FIG. 1, are not part of the
design.

The broken line showing of a watchcase and band portions
are environmental only and form no part of the claimed
design.
